(57) **CLAIM**

The ornamental design for an image sensor, as shown and described.

DESCRIPTION

FIG. 1 is a front perspective view of the front, left, and top sides of an image sensor showing our new design;

FIG. 2 is a rear perspective view of the rear, right, and bottom sides thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom view thereof;

FIG. 9 is an enlarged view at a part 9–9 of FIG. 1;

FIG. 10 is an enlarged view at a part 10–10 of FIG. 2;

FIG. 11 is an enlarged view at a part 11–11 of FIG. 3; and, FIG. 12 is an enlarged view at a part 12–12 of FIG. 8.

Broken lines and unshaded portions contained within broken lines depict exemplary elements of the image sensor that are shown for illustrative purposes only and that form no part of the claimed design. The dash-dot lines represent the boundary between the claimed design and unclaimed design.
